UNITED STATES PATENT OFFICE.

EDWIN W. PAPE, OF ST. LOUIS, MISSOURI, ASSIGNOR TO CRESCENT STOVE WORKS,
OF VANDERBURGH COUNTY, INDIANA, A CORPORATION.

AIR-CIRCULATION CONTROL FOR INCLOSED STOVES.

Application filed April 3, 1926. Serial No. 99,520.

This invention relates to that general class of stoves which have an outer shell or casing between which and the stove the air circulates and, usually, finds its outlet through 5 the top of the casing or shell.

Stoves of this general class have not, so far as I am aware, heretofore been provided with air circulation controlling means other than dampers of well known construction 10 and operation.

The object of my invention is to provide an entirely new type of heated air circulation control, to effect new results. With that end in view, the invention contemplates the provision of shutters located at the side or sides of the shell or casing and which may be fully closed, fully opened, or partially opened for the purpose of regulating and changing the circulation of the air and 20 the radiation of the heat in a new manner not obtainable by the use of ordinary dampers by which the flow and volume of air alone is controlled as distinguished from the direction of the flow.

25 A practical embodiment of the invention contemplates the provision of pivotally horizontally arranged shutters, coupled together to move in unison and located on opposite sides of the shell or casing, provision 30 being made for control of the shutters so that their position may be changed at will. When the shutters are closed all of the heated air is circulated between the outer casing or shell of the stove and the stove 35 itself which is inclosed within the shell or casing, such heated air passing through openings in the upper part of the shell and out into the upper part of the room before such heated air can return to the lower part 40 of the room. However, when the shutters are partially opened, say about half way open, the heat from the inclosed stove or heater will radiate through the spaces between the shutters and be deflected downwardly toward the floor, aside from the heated air flowing upwardly within the shell and out through the openings in the top of the latter. If the shutters are fully 45 opened there will be more direct radiation from the inclosed stove and toward the floor, thus radiating the heat more to the lower part of the room and naturally lessening the volume of heated air which rises within the shell or casing and passes out 50 through the openings in the top of the latter.

My improvements, therefore, are readily distinguished from the ordinary damper control because the latter makes no provision for directing radiation outwardly and downwardly from the stove, whereas with 60 my invention such adjustment of the shutters may be effected that the relative proportions or volumes of radiated heat directed downwardly and directed upwardly may be regulated at will. 65

My improvements are well adapted for use in connection with those inclosed stoves which have an ornamental or cabinetlike exterior appearance but they may be used in connection with any inclosed stove type of 70 heater.

In the drawings:

Figure 1 is a perspective view of a stove or heater equipped with my improvements, the shutters at the left hand side of the shell 75 being present but not appearing;

Figure 2 is a front elevation, the shell or casing being broken away to show the stove which is inclosed within the shell; and

Figure 3 is a detail perspective view, 80 broken away, showing certain of the shutters and the frame in which they are mounted.

The metal casing or shell appears at 1, and the stove or heater contained therein is 85 shown at 2, said shell and stove or heater being separated by an air space 3 for the circulation of the heated air. The fire box door is shown at 4 and the ash pit door appears at 5. The top of the shell 1 has openings or a grill work 6 to permit the heat to escape therethrough. 90

Doors 7 are provided to afford access to the stove 2 and to complete the inclosure of the stove so that it will not be visible. 95

My invention has nothing to do with the ordinary damper control of a stove or heater such as has been heretofore proposed but, on the contrary the purpose is to control the circulation of the heated air and the distribution of the heat by radiation downwardly and outwardly, as previously set forth. 100

Both sides of the shell or casing 1 are provided with shutters 8 which are mounted so that they may be completely closed, partly 105 opened, or fully opened. Preferably, the shutters are carried by a frame 9 to which they are pivoted in any suitable manner at both of their ends as shown at 10. By mounting the shutters 8 in a frame 9, the 110

entire shutter arrangement may be assembled separably from the stove and installed on the stove as a unit. It will be understood, however, that the shutters 8 may be directly 5 pivoted to the shell or casing 1 and that the frame 9 may be dispensed with.

Any suitable operating means may be employed for closing and partially or fully opening the shutters 8. I have illustrated 10 a vertical link 11 which is pivoted at 12 to an ear 13 on each shutter, but other arrangements could be resorted to. The link 11 may be operated by any suitable manually controlled device, such for instance, as shown 15 at 14. By coupling the shutters 8 together they are adapted for simultaneous setting, at the will of the user of the stove, so that all of them will be arranged at the same angle.

20 By preference the shutters 8 have a flange 15 to enable them to be tightly closed together and for the purpose of strengthening them and preventing buckling.

The shutters 8 and the frame 9 are of sheet 25 metal of suitable gage.

The side walls of the shell or casing 1 are provided with openings into which the frames 9 are set, said frames then being secured to the shell or casing 1 in any desired manner.

As previously set forth, when the shutters 8 are closed, they form, in effect, a closed side wall for the shell 1. The heated air then circulates between the shell and the 35 stove 2, passing out through the openings 6 and rising to the top of the room before returning to the lower part of the latter.

When the shutters 8 are partially opened, that is, about half of the way, as shown for 40 instance in Figure 1, the heat from the stove 2 will radiate through the spaces between the shutters and be deflected by the shutters down towards the floor, while heated air flows upwardly within the shell and out 45 through the openings 6 in top grill.

When the shutters are fully opened as shown in Figure 3, for instance, there will be a more direct radiation from the stove through the openings between the shutters 50 and down toward the floor so that a lesser amount of heated air will flow upwardly between the shell 1 and the heater 2.

Thus, the user, by setting the shutters 8 in different positions, may vary the circulation 55 of the heated air and also the radiation of the heat, according to requirements.

It is to be understood that in the use of the words "shutter" or "shutters" in the claims, I do not limit myself to the specific 60 construction and arrangement of shutters hereinbefore described and which are shown in the drawings, nor is the invention limited to disposing the shutters on the sides of the shell or casing nor to their use on both 65 sides of said shell.

I claim:

1. The combination with a stove or heater, of an inclosing shell or casing therefor, and regulable means carried by said shell whereby the heat within said shell may be radiated outwardly from the shell in different predetermined directions according to the setting of said regulable means. 70

2. The combination with a stove or heater, of an inclosing shell or casing therefor, and 75 regulable deflectors carried by said shell whereby the heat within said shell may be radiated outwardly from the shell in different predetermined directions according to the setting of said deflectors.

3. The combination with a stove or heater, of an inclosing shell or casing therefor, and regulable means carried by said shell adapted for radiating the heat from within the shell outwardly and downwardly in relation 85 to the shell in different predetermined directions according to the setting of said regulable means.

4. The combination with a stove or heater, of a shell or casing therefor, and controllable deflectors adapted to be set in different positions to radiate the heat from within the shell outwardly therefrom in different predetermined directions, according 95 to the setting of said deflectors, said deflectors being also adapted to be closed to limit the radiation.

5. The combination with a stove or heater, of an inclosing shell or casing therefor, and swingingly mounted shutters carried by said shell which are adapted to be closed or to be set in different open positions, whereby the heat may be prevented from radiating past 105 said shutters, or, may be radiated outwardly, or downwardly, from said shell in different predetermined directions according to the setting of said shutters.

6. The combination with a stove or heater, of an inclosing shell or casing therefor, said shell having in an upright wall thereof a 110 group of connected, pivoted, horizontally arranged, shutters which may be closed, or, opened to assume different angles whereby the heat may be radiated from said shell past said shutters in different predetermined directions according to a setting of said shutters.

7. The combination with a stove or heater, of an inclosing shell or casing therefor, and regulable means carried by said shell whereby the heat within said shell may be radiated outwardly from the shell to different extents according to the setting of said regulable means. 120

8. The combination with a stove or heater, of an inclosing shell or casing therefor, and regulable means carried by said shell whereby the heat within said shell may be radiated outwardly from the shell to different extents according to the setting of said regulable means. 125

ulable means, and the circulation of the heated air within the shell or casing may also be varied.

9. The combination with a stove or heater, 5 of an inclosing shell or casing therefor, there being an air space between the stove or heater and the shell or casing, and regulable means carried by the shell or casing adapted for exercising a joint or combined 10 control over the radiation from the heater into the room it occupies and on the rising air currents in the air space aforesaid.

10. The combination with a stove or heater, of an inclosing shell or casing therefor, there being an air space between the stove 15 or heater and the shell or casing, and a regulating set of shutters, acting as combined air shutters and reflectors, whereby common or joint control may be exercised over the radiation from the heater into the 20 room it occupies and on the rising air currents in the air space aforesaid.

In testimony whereof I affix my signature.
EDWIN W. PAPE.
